UNITED STATES PATENT OFFICE.

EDMUND KAIM, OF JERSEY CITY, NEW JERSEY, ASSIGNOR TO JACOB KOENIG, OF JERSEY CITY, NEW JERSEY.

DESIGN FOR A NICHE.

Application filed August 8, 1927. Serial No. 23,025. Term of patent 14 years.

To all whom it may concern:

Be it known that, I, EDMUND KAIM, a citizen of the United States, residing in Jersey City, in the county of Hudson and State of New Jersey, have invented a new, original, and ornamental Design for a Niche, of which the following is a specification, reference being made to the accompanying drawing, forming part thereof, in which—

Fig. 1 represents a side elevation of a niche embodying this invention.

Fig. 2 is a top view of the same.

I claim:

The ornamental design for a niche as shown.

EDMUND KAIM.
